UNITED STATES PATENT OFFICE.

GEORGE ALVAH McLANE, OF NEW YORK, N. Y.

IRONING DEVICE.

SPECIFICATION forming part of Letters Patent No. 626,792, dated June 13, 1899.

Application filed March 29, 1899. Serial No. 710,905. (No model.)

To all whom it may concern:

Be it known that I, GEORGE ALVAH McLANE, a citizen of the United States, and a resident of New York, (Brooklyn,) county of Kings, and State of New York, have invented 5 certain new and useful Improvements in Ironing Devices, of which the following is a specification, reference being had to the accompanying drawings, forming a part thereof, in which similar letters of reference indicate corresponding parts.

This invention relates to ironing devices; and the object is to provide an improvement over the device described and claimed in my 15 application filed February 7, 1899, Serial No. 704,844.

The invention will be hereinafter fully described, and specifically set forth in the annexed claims.

20 In the accompanying drawings, Figure 1 is a perspective view of the device. Fig. 2 is a longitudinal sectional view of one of the boards.

In constructing my device I employ a series 25 of double boards *a*, having preferably rounded faces. The upper board *b* preferably has a plane face and is spaced apart from the lower board *c* by means of a series of posts *dd*. The lower board *c* has a series of perforations *ee* 30 therein.

In the operation of the device the clothes are taken from the washtub and wrung out as dry as possible. One of the boards *a* is then placed upon the floor or table and the 35 fabric stretched upon the upper plane face. Another board is then placed upon the fabric with the perforated face in contact therewith. Then another piece of fabric is placed upon the plane face of this second board and the 40 perforated face of the third board placed upon

the fabric, and this operation is continued until all the clothes have been placed between the boards in one pile. The weight of the boards on the fabric will create the desired pressure and the fabric as stretched will dry 45 perfectly smooth, the plane faces of the boards carrying off any water which may be pressed out of the fabric and allowing it to drip over the edges of the device, while the air has a free circulation between the two parts of the 50 board and reaches the fabric through the perforations *ee*.

Having thus described my invention, what I claim as new, and desire to secure by Letters Patent, is—

1. In an ironing device, the combination of a series of double boards between which the fabric is stretched, the members of said boards being spaced apart and the lower member provided with perforations, the upper member 55 having a plane face, substantially as described.

2. In an ironing device, the combination of a series of double boards, a series of posts spacing the members of said boards apart, 60 perforations in the lower member communicating between said space and the fabric, the upper member being adapted to drain the water pressed out of the fabric and discharge it over the edge of the device, substantially 70 as described.

In testimony that I claim the foregoing as my invention I have signed my name, in presence of two witnesses, this 27th day of March, 1899.

GEORGE ALVAH McLANE.
